UNITED STATES PATENT OFFICE.

EUGENE F. DAVENPORT, OF MELROSE, MASSACHUSETTS, ASSIGNOR TO UNITED SHOE MACHINERY COMPANY, OF PATERSON, NEW JERSEY, A CORPORATION OF NEW JERSEY.

LEATHER-SKIVING MACHINE.

1,121,717.

Specification of Letters Patent. Patented Dec. 22, 1914.

Application filed July 17, 1909. Serial No. 508,136.

To all whom it may concern:

Be it known that I, EUGENE F. DAVENPORT, a citizen of the United States, residing at Melrose, in the county of Middlesex and State of Massachusetts, have invented certain new and useful Improvements in Leather-Skiving Machines; and I do hereby declare the following to be a full, clear, and exact description of the invention, such as will enable others skilled in the art to which it appertains to make and use the same.

The present invention relates to a device for sharpening and removing the bur from the edge of the knife of a leather skiving machine and is intended primarily for use in machines of the type disclosed in an application for United States patent filed by George E. Warren, Serial No. 481,117, dated March 3, 1909. It is to be understood, however, that while the invention is particularly adapted for use in machines of the class disclosed in said application, the invention is also applicable to other forms of leather skiving machines.

In the skiving machine above referred to the pieces of leather to be skived are fed to a rotary cylindrical knife by means of a feed roll coöperating with a presser foot. It is essential that the edge of this knife be maintained sharp so that the leather may be skived to a very thin edge. Heretofore machines of this general class have been provided with a grinder mounted so as to be capable of being brought into engagement with the outer surface of the knife. This grinder leaves a bur at the edge of the knife and it has been customary to remove this bur by means of an oil stone held in the hand of the operator. This method of removing the bur is objectionable for the reason that the knife is not readily accessible and for the reason that there is danger of the operator being cut by the knife. Another objection to this method of removing the bur is that the whet stone is not always manipulated properly by the operator so that the edge of the knife is not left in a condition to do satisfactory work.

The object of the present invention is to provide a sharpening and bur removing device which will be free from the objections above noted, which will be simple and compact in construction, and will perform the desired operations in a satisfactory manner.

With this object in view the present in-

vention contemplates the provision of an oil or whetstone supported adjacent to the cutting edge of the knife, and mechanism for moving the stone into and out of operative relation with the knife edge and for permanently supporting the stone with its working face positioned in parallel relation to the interior surface of the knife.

In the preferred form of the present invention, certain novel constructions and arrangements of parts are provided which are hereinafter described and claimed. The advantages of these constructions will be apparent to those skilled in the art from the following description and an inspection of the accompanying drawings.

In the drawings Figure 1 is a partial sectional side elevation. Fig. 2 is a partial sectional plan view, and Fig. 3 is a sectional end elevation.

As shown in the drawings the machine comprises a base 1 the left hand or front end 2 of the top of which forms a work table upon which an edge gage 4 is adjustably mounted. A presser foot 6 is mounted in a head 8 and adapted to coöperate with a feed roll 10 directly below the same to feed the material to be skived. The feed roll is rotatably supported by an arm 12 which projects laterally from a sleeve 14 rotatably mounted on a rod 15 which is supported in the base of the machine. The sleeve 14 is surrounded by a coiled spring 16 which is attached at one end to a lug 18 on the sleeve and at the other end to a collar 19 pinned to the rod 15. Thus the feed roll is yieldingly pressed upward against the material to be skived. A knob 20 is connected by means of a rod 21 to a depending arm 22 on the sleeve 14, by means of which feed roll may be manually lowered to allow the operator to insert the material between the feed roll and presser foot. The feed roll is rotated by means of a rod 24 having a universal joint at each end and connecting the roll with a shaft 26 provided with a spiral gear 27 meshing with a similar gear 28 on a shaft 29 connected to any suitable source of power. The feed roll is mounted to rotate near the edge and within the periphery of a cylindrical skiving knife 30.

The knife 30 is secured to the flanged end 32 of a shaft 34 journaled to rotate in a sleeve 36 mounted in a frame 37 supported by the base of the machine. The shaft 34

2
is rotated by any suitable means. For sharpening the edge 38 of the knife a rotary grinding disk 40 is provided which is mounted upon the upper end of a shaft 42 journaled in a boss 44 formed on one end of a swinging arm 46. A grooved pulley 47 is mounted on the lower end of the shaft 42 and is driven by a belt 48 connected with the source of power. A screw-threaded rod 50 is pivotally connected at one end to the arm 46 by a pin 51 and projects through the side of the base 1 to cooperate with a long sleeved nut 52 by means of which the position of the grinding disk may be varied. If desired a spring (not shown) may be connected to the arm 46 to draw the disk against the knife when the nut 52 is unscrewed.

The parts of the machine so far described are the same in construction and mode of operation as the corresponding parts of the machine disclosed in the application hereinbefore referred to.

The construction illustrated in the drawings as embodying the preferred form of the present invention comprises an oil or whet stone 60 in the form of an elongated cylinder. This stone projects into the interior of the rotary knife and is mounted in a holder or boss 61 provided with a clamping or set screw 62 and mounted upon an arm 64 pivoted at 65 to a bracket 66 attached to the side of an arm 68 secured to the frame 37 and projecting below the knife. The plane of movement of the arm 64 into and out of operative position is parallel to the plane of the cutting edge of the knife and the stone is secured in the arm normally to this plane so that with this construction the working face of the stone is permanently positioned in parallel relation to the interior surface of the knife. A rod 69 is pivotally attached at one end to the arm 64 and projects through the base 1 the outer end of the rod being provided with a knob 70. A spring 72 surrounds the rod 69 and is interposed between the outside of the base 1 and the inner end of the knob

70. This spring tends to keep the stone 60 away from the edge of the knife, and this movement may be limited by a pin 74 on the rod 69 coming in contact with the inside of the base.

In operation, the nut 52 is unscrewed to allow the grinding disk 40 to sharpen the edge 38 of the knife. The grinding disk is then withdrawn and the bur produced by the grinding operation is removed by the stone 60 which is brought into contact with the interior of the knife by pushing the knob 70 against the tension of the spring 72. Upon releasing the knob the stone is automatically withdrawn from contact with the knife.

The invention having been described, what is claimed is:—

1. A leather skiving machine, having, in combination, a substantially cylindrical skiving knife, a grinding disk arranged to be moved at intervals into contact with the exterior beveled surface of the knife to sharpen the cutting edge, a whetstone projecting within the knife, and mechanism for moving the stone into and out of operative relation with the knife edge and for permanently supporting the stone with its working face positioned in parallel relation to the interior surface of the knife and extending substantially in the direction of the axis of the knife.

2. A leather skiving machine, having, in combination, a cylindrical skiving knife, a grinding disk arranged to contact with the exterior surface of the knife to sharpen the cutting edge, an arm arranged to move in a plane parallel to the plane of the cutting edge, and a whetstone secured in the arm and projecting within the knife normal to the plane of the movement of the arm and with its working face parallel to the interior surface of the knife.

EUGENE F. DAVENPORT.
